CIRCULATING HEATER

Ivan F. Henshaw, Richmond, Va., assignor to Automatic Draft and Stove Co., Inc., Lynchburg, Va., a corporation of Virginia

Application January 10, 1957, Serial No. 44,467

Term of patent 14 years

(Cl. D81—19)

Figure 1 is a perspective view of a circulating heater embodying my design;

Figure 2 is a front elevation thereof, the rear being substantially plain except as indicated in Figs. 3 and 4;

Figure 3 is a side elevation; and

Figure 4 is a plan view.

The dominant features of the design reside in the portions shown in full lines.

I claim:

The ornamental design for a circulating heater, as shown and described.
